UNITED STATES PATENT OFFICE

WILLIS H. YOUNG, OF POMPTON LAKES, NEW JERSEY, ASSIGNOR, BY MESNE ASSIGNMENTS, TO NORMAN C. MENDES, OF NEW YORK, N. Y., TRUSTEE OF EVERNU CORPORATION, BANKRUPT

HAT PROTECTOR

Application filed June 12, 1926, Serial No. 115,428. Renewed January 11, 1929.

This invention relates to wearing apparel and has particular reference to means for protecting from the damaging effect of inclement weather head coverings and especially hats worn by women or men.

Among the objects of the invention is to provide a device of a relatively simple and cheap structural nature adapted when in use to protect a lady's hat from rain in a manner that is both efficient as to the protection and inconspicuous as to appearance while being worn, and so devised as to be carried in one's pocket, purse, shopping bag, or vanity kit, so as to occupy space barely over two inches in diameter and about a quarter of an inch in thickness when not in use but in anticipation of possible inclement weather.

Another object of the invention is to provide a device of the nature set forth that is calculated to appeal to the aesthetic, it being possessed of features calculated to be immediately decorative or ornamental, and yet at the same time serving as indicating means for functional purposes.

More specifically, the device in the main comprises a flexible thin elastic bag portion of waterproof material to which is attached a receptacle or container likewise of flexible material and very much smaller in compass than the bag but adapted to contain the bag so as to constitute the whole as a self contained structure for the purpose of convenience in carrying.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a diagrammatic perspective view showing the device in operation upon a hat.

Fig. 2 is a bottom plan view of the device in the form adapted for direct application to the hat, the container portion being in-

dicated within the top or crown portion of the bag.

Fig. 3 is a side elevation, partly in section, showing the bag turned inside out and ready to be gathered or stuffed within the receptacle.

Fig. 4 is a plan view of the device in nested form.

Fig. 5 is a sectional view of the same on the line 5—5.

Referring now more specifically to the drawings I show my improvement as comprising a main cover member or bag 10 made of thin elastic waterproof material such as sheet rubber or its equivalent of any suitable color or shade and of normal size sufficient to cover easily, with at most moderate extension, any ordinary hat. While the normal size or dimensions of the bag portion 10 may be comparatively extensive such as from eight to twelve inches in length, the mass of the material is not very great because of the thinness of the stock. The bag is provided with a large opening or mouth 11 bounded by a rim portion 12 sufficiently constructed to make the mouth portion of the bag materially smaller than the main body thereof, thereby facilitating the securing of the device in place in use and improving the waterproof properties thereof. The nature of the binding 12, moreover, is calculated to strengthen the edge portion of the bag. Otherwise the bag is imperforate and has a generally smooth rounded or elliptical contour when open or extended.

One of the principal features of novelty of my improvement consists of a container or receptacle 13 in the nature of a flat circular pouch having in one side a circular opening 14, the diameter of which is about one-third of the normal diameter of the container. I wish it to be understood, however, that as to these or any other dimensions mentioned herein I do not wish to be limited unnecessarily, such dimensions being referred to merely for the sake of clearness of description instead of limitations. This element 13 like the bag is made preferably of thin elastic material such as a good quality sheet rubber. To the inside surface of the imperforate side

portion of the container 13 is secured in any suitable manner as by the use of cement or the like at 15 the top of the crown portion of the bag. The point of application to the bag may be thought of as a point of the inner surface of the protector when worn.

Cemented or otherwise secured to or formed upon the outer surface of said imperforate side of the container 13 is an ornamental or indicator feature shown in the nature of a daisy or other blossom 16, the petals of which may be fastened down against the surface of the container or not as may be desired, the fastening between the ornament 15 and the container being mainly at the head or ball of the blossom. The flower serves to identify that side of the container to which it is attached and constitutes an element of distinct ornamentation or embellishment for the combination device. This ornamentation 16 is made of any suitable material but as practised by me extensively it is cut or stamped from sheet rubber of suitable colors according to the nature of the flower represented thereby.

As above premised the device is adapted to be nested and carried in one's pocket or shopping bag in the form shown in Figs. 4 and 5, occupying about as much space as a man's 30 watch, but in the event of sudden downpour the person carrying it simply removes it from her bag or purse and grasps it between the thumbs and fingers of both hands, the fingers engaging within the hole 14 while the thumbs 35 press toward said hole against the face of the ornament 16, such movement being continued until the container is turned directly inside out, thus delivering the bag bodily and wholly therefrom as in Fig. 3. The bag 40 is then free to be applied to the hat directly, but preferably it is reversed so as to bring the container 13 upon the inside as shown in Fig. 2 where it occupies practically no space and is either invisible or inconspicuous. 45 After the portector has served its purpose as such and is removed from the hat it may be restored to normal nested position or form by bringing it back to the position of Fig. 3, when the operator will grasp the rim of the 50 hole 14 again with her fingers as previously described, while with her thumbs she will gather and stuff the bag bodily into the container while the latter is being turned inside out again to bring it around the bag as shown in Fig. 5. The stock from which the bag is 55 made is so light and flexible that it may be gathered and crumpled readily into the small space that is demanded. With a very easy 60 and quickly determined adjustment of the bag it may be formed into substantially flat disk position to accommodate it to the small space within the receptacle 13 and with the ornament 16 on the outside or face as already 65 set forth.

I claim:

The herein described combined hat protector and container, the protector being in the nature of a large bag of thin elastic material having an opening at one end, while the 70 container is in the nature of a small receptacle and likewise of elastic material and provided in one side with a small opening, the bag and the container being attached directly together at points remote from the 75 openings of said protector and container whereby in one position they are otherwise free from each other but adapted to be manipulated to bring the bag inside of the container.

In testimony whereof I affix my signature.

WILLIS H. YOUNG.
